UNITED STATES PATENT OFFICE.

ALLERTON S. CUSHMAN, OF GREENWICH, CONNECTICUT, ASSIGNOR TO THE AMERICAN ROLLING MILL COMPANY, OF MIDDLETON, OHIO, A CORPORATION OF OHIO.

CORRUGATED-METAL CULVERT.

Continuation of application Serial No. 9,021, filed February 13, 1925. This application filed June 17, 1926. Serial No. 116,689.

My invention relates to corrugated metal culverts which are very widely used for all kinds of drainage and sewage purposes and this application is a continuation of my former application Serial No. 9021, filed February 13, 1925. The culverts involved in this invention are made as full circle culverts and of the nestable types, from thin light corrugated metal, and the sections are secured together to form a continuous corrugated culvert in a variety of ways.

These culverts are formed of sheets corrugated and bent into tubular form, the longitudinal edges being secured together by riveting, or otherwise, as desired. The longer culverts are made up of shorter sections by inserting the sections end to end into telescoping relation and, if desired, further securing them together by rivets, bolts or the like. Two or more of the shorter sections may be secured together at the factory, or elsewhere, and the desired number thus joined shipped to the place of installation where they may be still further secured together end to end to form a culvert of any desired length. Or if desired the individual sections may be shipped separate and secured together where installed, or if its length is not too great the culvert may be shipped complete. The particular procedure followed in this regard will be as desired for the existing conditions.

The corrugated culvert is recognized as taking an important place in industry due to certain factors thereof which should be noted. The strength factor imparted by the corrugations permits of the culvert being made of relatively thin metal, and still able to withstand the great strains incident to the support of fills of earth, heavy traffic, and allow for expansion and contraction under different climatic conditions and other causes. This makes for inexpensiveness and relatively small weight.

The corrugations lock themselves into the earth of fills, preventing displacement and holding the earth against movement adjacent to the bodies of the culverts, thus obviating the danger of the culvert being washed out in whole or in part or being disrupted.

The corrugated type of metal culvert lends itself to a simple and strong lapped joint, by

thrusting the end of one culvert into the end of another in line therewith, and then riveting. Also long sections can be joined on the job in the same manner, using bolts, hooks, or other suitable fastening means. Also corrugated bands can be employed to surround a butt joint. The sections are so joined together as to make a rigid integral structure corrugated from end to end, so that they will intermesh or interlock with the earth through their entire length and circumference.

The cylindrical, circumferentially corrugated culverts withstand great strains tending to flatten or crush them by giving way to the weight of the earth above (shortening of the vertical diameter) and seeking side support from the earth at the sides (lengthening of horizontal diameter). As shown by recent tests the corrugated culvert tends under the pressure of embankments to take an elliptical shape and the pressures at the top and sides are equalized. This is contrary to the behavior of rigid types of culverts where the culvert must carry the load of the embankment without material deflection, for here deflection causes fracture and subsequently failure.

Investigations of thousands of culverts in actual service from one to twenty years have shown that the life of the metal culvert of the corrugated type is terminated by the failure of the bottom section of the culvert to resist the effects of abrasion and corrosion. While the culvert sections are well galvanized as usually produced, it is well known that the galvanized coating, which is applied to resist corrosion, is not highly abrasive resistant. The unevenness of the interior of the body of the culvert due to the corrugations leads to a churning about of the particles of abrasive matter, pebbles, sand, and the like which tends to scour off the galvanized coating and expose the base metal. Once the base metal is exposed corrosion becomes a factor, the continued scouring removing rust films as fast as formed and thus hastening the deterioration of the bottom section by a combination of corrosion and erosion. Also where the joints of the sheets which make up the culvert sections come at the bottom of the culvert when laid,

this churning and abrasive action is further accelerated. For this reason the joints are usually set in alternate series at 90° to the vertical median plane of the culvert and 5 on each side thereof.

The problem presented has been recognized in the art, and many efforts have been made to provide against the unevenness of the bottom of the culvert where the abrasive 10 action comes. Culverts have been made with round bottoms or inserts free of corrugations, or with perfectly flat bottoms, but these did not satisfactorily solve the problem, as many of the advantages of the complete circumferential corrugation were sacrificed, such as strength, toughness, lightness, 15 locking with the earth below and expansion and contraction.

Culverts are shipped to the roughest kind 20 of country where new roads and fills are being made, and as a result receive very rough handling and usage. Substances used to remedy the defects incident to long use of these otherwise very valuable culverts 25 must withstand the strains of expansion, contraction and deflection in use without any considerable extra weight, or added pieces, or fragile or brittle structures within the culvert sections.

30 Furthermore the necessary function of deflection of the culverts, requires that any attempt to prevent the unevenness of the bottom floor of the culvert be accomplished with such material as will not break when this 35 deflection takes place.

One of the objects of my invention is to provide for corrugated culverts a coating of material having certain essential features, which result in the provision of an adequate, 40 inexpensive and permanent method of maintaining all of the advantages of the cylindrical, circumferentially corrugated culvert, including resistance to great strains both from without and within, resistance to strains 45 from freezing, and the like, (the culvert being constructed to yield slightly under loads before approaching the point of failure), with the additional great advantage of being fully protected against that abrasive action 50 which has heretofore been the only real drawback to universal acceptance of the devices in question in the place of cast iron or concrete tiles.

As the result of many experiments I preferably employ in my coating a bituminous 55 body having high surface adhesion so that it clings tightly to the culvert surface, a permanent resiliency so that it will neither crack nor break when subjected to deflection 60 in use, and which will adhere to the portion of the culvert to which it is applied under all of the varying conditions to which the culvert is subjected in use. It must have an absence of brittleness so that it will withstand 65 rough handling, and a high degree of

inertness so that it will substantially resist all chemical and galvanic action and have such toughness as will withstand the abrasive action of sand, pebbles and the like over a long period of time without wearing 70 away or exhibiting fatigue.

In its physical structure my coating is preferably cut down to a thin layer over the culvert surface except along the base line thereof, when laid. The coating at the base 75 line should be applied in sufficient quantities to fill up the corrugations at the bottom of the culvert, either practically to the apices thereof, or to cover them. It may be considered in some instances advantageous 80 to coat the entire interior or exterior or both, of the culvert with a paint-like film, but it will always be desirable in addition to the filling of the corrugations at the bottom, to coat the inside of the lower portion 85 of the culvert above the filling. However, the ultimate essential is the filling of the corrugations of the culvert along the base line thereof, where the greatest eroding action and wear takes place when the culvert is in 90 use.

Thus in its essence my coating serves as a substantially smooth floor for the culvert lengthwise of the base thereof, with the highly desirable extension of a film-like 95 coating up the side of the bottom section of the structure. The advantages of this are that but little weight is added, and by filling the interior depressions of the corrugations along the base line the point of danger is 100 protected, in a manner which is permanent and secure, and the coating material becomes a part of the culvert itself, tightly adhering thereto, and yielding simultaneously with the yield of the culvert sections without being severed therefrom or otherwise disrupted.

One of the advantages of the type of protective coating briefly noted, and to be more 110 specifically described, is that it is susceptible of formation by merely spraying the culvert, or culvert section, or dipping it and holding it substantially horizontal so that all of the material will flow away which is in excess of that covering the sides and filling the interior depressions of the bottom corrugations. Further it adapts itself for 115 use with materials which are heat plastic and quick setting, such as bituminous materials, which exhibit in their qualities the required factors, and provide the protection desired without involving any disadvantages.

Another feature of my improved resilient 120 or elastic coating material is that it best resists the abrasive action of sand, gravel, and the like. This makes possible the use of the highly desirable corrugated culvert without the heretofore serious defect of the wearing away of the culvert bottom by abrasion or 125

erosion by sand, gravel and other materials passing therethrough, and without detracting in any way from the numerous advantages possessed by such corrugated culverts.

5 Further objects, advantages and capabilities will hereafter more fully appear.

My invention further resides in the combination, construction and arrangement of parts illustrated in the accompanying drawings, and while I have shown therein a preferred embodiment I wish the same to be understood as illustrative only and not as limiting the scope of my invention.

In the drawings:

15 Figure 1 is a side elevation, partly in section, of a typical culvert formed of sections riveted together and coupled in lengths.

Figure 2 is a section on the line 2-2 of Figure 1.

20 Figure 3 is a side elevation of a joining band.

Figure 4 is a perspective of a section of a culvert section, showing the novel coating and filling applied thereto.

25 Figure 5 is a fragmentary section taken horizontally through the device shown in Figure 4, and looking down, and on line 5-5 of Fig. 6.

Figure 6 is a fragmentary section taken vertically through Figure 4.

30 Shown in Figure 4 is a single culvert section formed of a sheet 1 provided with lengthwise corrugations 2, 2^a and formed into a corrugated cylinder, with a lap joint at 3, secured by means of rivets 4. The corrugations are indicated with internal crests marked 2, and external crests marked 2^a.

The culvert sections indicated generally at 5 in Figure 1, are joined together end to end by omitting a rivet or so at one end of each section, and spreading the end of one section so that it engages over a previous section as indicated by the telescoping or lapped joints at 6 (Figure 1). The lap joint 3 of each section, in forming the long culvert is turned oppositely to the joint 3 of the section to which it is attached. Rivets 7 set in place around the joints 6 between sections serve to hold them permanently together.

35 In joining together the culvert sections on the job, I preferably provide the band type of union. This comprises a narrow corrugated cylindrical section 8, having brackets 9 at the ends, through which the tightening bolts 10 are passed.

40 Each culvert section terminates at each end with an external crest 2^a, and the long culvert naturally terminates in the same manner. In joining culverts together they are 45 in some instances butted against each other, and bands are set over the meeting ends and these bands are then clamped tightly by means of the bolts. Due to the corrugated structure of the sections and the band, the

culverts are keyed tightly together preferably by the form of union shown.

The sheets can be galvanized before or after being formed into culvert sections, or may be formed into culvert sections, then united into full length culverts and finally galvanized, if desired.

When the culvert is of the nestable type the nestable sections are assembled for use and treated in the same manner as the full circle culverts herein described and embodying my invention.

The provision of the protective coating is made after the culvert is of full shipping length and has been galvanized. The coating is preferably applied by means of spraying or dipping, and the culvert held in substantially a horizontal position during solidification of the material applied to the culvert; however, it may be applied in other ways if desired, and either before shipping or on the job.

In the instance of dipping, the culvert is held substantially horizontally and dipped into a trough containing a heat liquefied bitumen, which is of the type having a high surface adhesion and resilience, and which when set possesses a sufficient degree of expansion and contraction so as to respond to the expansion and contraction of the cylindrical corrugated sections to which it is applied, so as to prevent breakage and separation from the metal, and which is somewhat plastic when cold. Other material as a coating which has like or similar characteristics may be employed.

45 After the culvert has been dipped as low as desired into the bath of bitumen, it is elevated and held substantially horizontal until the excess has flowed away. Thus on the outside of the culvert all but a coating film will flow off, and on the inside all but a coating film will flow down to the central base line of the culvert, and thence out through the ends thereof. The material will thus fill the interior depressions of the corrugations along the base line of the culvert, and the culvert will be held in substantially horizontal position at least long enough for the liquid thus collected in the interior depressions of the corrugations to solidify.

50 In Figure 4 the result is shown graphically. There will thus be a coating or film 20 (shown exaggerated in Figure 4), on the outside of the culvert, and on the inside there will be a coating or film 21 (also shown exaggerated), at each side of the base central line, and a substantially smooth floor 22, which substantially fills the interior depression of the corrugations and covers the internal crests of the corrugations.

55 In Figure 4 the culvert was only dipped about half way and the coating thus only extends part way of the finished article.

This is merely the preferred result since it accomplishes full protection, with the least quantity of material. The coatings 20 and 21 may, of course, be extended entirely around the circumference if desired.

When applying the internal coating by spraying the spray will have to be continued long enough to fill the interior depressions of the corrugations at the base line.

16 The coating might, of course, be applied on the job, but without special equipment for doing this, certain technical difficulties due to the usual considerable length of the culverts, will be presented.

17 In applying the bands in joining culverts together, it may be desired to pour a small quantity of the coating material into the cavity left between the butted external ends, before the band is tightened up.

20 However, this is not necessary, as the occasional pockets left in the long culverts will fill up with silt. The section in Figure 2 shows at 23 a quantity of the bitumen poured into place prior to completing the joint.

21 It will be noted that the filling of the corrugations at the base of the culvert will likewise submerge the internal ledge where one tube section laps another in forming the culvert. Also, if the lap joints made in forming the tube sections from corrugated sheets happen to come at the base of the culvert, which normally is avoided, the coating will submerge this joint also.

25 Having thus described my invention, what I claim as new and desire to secure by Letters Patent, is:—

1. A sheet metal culvert having a lowermost portion formed as a part of a cylindrical surface corrugated circumferentially, and an inert, adhesive, plastic substance, free from brittleness when set, substantially filling the depressions of the corrugations of said portion internally thereof over an area confined substantially to said base, and covering the spaces between corrugations so as to present a surface along said base that is substantially free of depressions, for the purpose described.

2. A sheet metal culvert having a lowermost portion formed as a part of a cylindrical surface corrugated circumferentially and adapted to expand and contract, and an inert, adhesive, plastic substance free from brittleness when set, substantially filling the depressions of the corrugations of said portion internally thereof over an area confined substantially to said base, and covering the spaces between corrugations so as to present a substantially depression free surface along said base, said substance also coating the sides of the inside of said portion at least adjacent said filling with a relatively thin adhesive covering.

3. A sheet metal culvert having a lower-

most portion formed as a part of a cylindrical surface corrugated circumferentially, and adapted to expand and contract, and an inert, adhesive, plastic substance free from brittleness such as soft asphalt, substantially filling the depressions of the corrugations of said portion internally thereof over an area confined substantially to said base, and covering the spaces between corrugations so as to present a substantially depression free surface along said base, said substance also coating the sides of the inside of said portion adjacent said filling with a relatively thin adhesive covering, said substance also being applied as an adhesive coating on the outside walls of the said culvert.

4. A sheet metal culvert having a cylindrical body circumferentially corrugated, said body having a coating of soft asphalt, located on the inside thereof at least, covering the lower side walls with a tightly adherent coating, and filling the interior depressions of the corrugations of the culvert over an area confined substantially to said base, and submerging the corrugations and covering the spaces between them so as to form a substantially depression free floor lengthwise of the culvert.

5. A sheet metal culvert comprising a plurality of sections secured together end to end, each section having a cylindrical body circumferentially corrugated, said body having a coating of soft asphalt or its equivalent, located on the inside thereof at least, covering the lower side walls with a tightly adherent coating, and filling the interior depressions of the corrugations of the culvert, over an area confined substantially to said base, and submerging the corrugations and covering the spaces between them so as to form a substantially depression free floor lengthwise of the culvert.

6. A sheet metal culvert having a cylindrical body circumferentially corrugated, said body having a coating of soft asphalt, located on the inside thereof, covering the lower side walls with a tightly adherent coating, and filling the interior depressions of the corrugations of the culvert over an area confined substantially to said base, with a body that substantially submerges the corrugations, covers the spaces between them, and forms a depression free floor lengthwise of the culvert, said coating material also coating the exterior of the culvert with a relatively thin covering.

7. A corrugated metal culvert having on its interior adjacent the bottom a coating of adhesive non-brittle material resistant to abrasion, said material at the bottom of the culvert filling the interior depressions of the corrugations over an area confined substantially to said bottom and covering the space between the depressions so as to form a substantially depression free surface to

- resist abrasion and corrosion of the corrugated bottom by materials passing through the culvert.
8. A corrugated metal culvert having the interior depressions of its bottom corrugations substantially filled and the spaces between them covered with an adhesive abrasion-resisting material tenaciously adhering to the culvert bottom over an area confined substantially to the culvert bottom to form a surface substantially free from depressions so as to prevent abrasion of the culvert bottom by materials passing therethrough.
15. 9. A corrugated sheet metal culvert comprising a plurality of cylindrical sections secured end to end, the valleys and crests of the corrugations in each section extending circumferentially, the lower portions of the inner surface of said culvert being coated with an adhesive flexible substance of abrasion-resisting nature, a portion of said coating substance substantially filling the interior depressions of the corrugations and covering the spaces between them over an area confined substantially to the base of the culvert to provide a substantially depression free surface in the bottom of the culvert to prevent abrasion by materials passing therethrough.
10. A corrugated sheet metal culvert comprising a plurality of cylindrical sections secured end to end, the valleys and crests of the corrugations in each section extending circumferentially, the lower portion of the inner surface of said culvert being coated with an adhesive flexible substance of abrasion-resisting natures, and a portion of said coating substance substantially filling the interior depressions of the corrugations and covering the spaces between them over an area confined substantially to the base of the culvert, to provide a substantially depression free surface in the bottom of the culvert to prevent abrasion by materials passing therethrough, and filling and covering any joints in or between the sections, occurring along the base portion of the culvert.
11. A sheet metal culvert having its lowermost portion formed as an arc shaped surface corrugated circumferentially to expand and contract under different strains and climatic conditions, and an inert adhesive plastic substance, substantially filling the valleys of the corrugations along the base and confined substantially to the base of said portion internally thereof, and covering the spaces between valleys thus presenting substantially an uncorrugated surface along said base, said filling possessing a sufficient degree of expansion and contraction so as to practically synchronously respond to the expansion and contraction of said lower portion, thereby preventing disruption of the filling and separation of the filling from the metal.
12. A sheet metal culvert having a lowermost portion formed as a part of a cylindrical surface corrugated circumferentially, and an inert, adhesive, plastic substance, free from brittleness when set, substantially filling the depressions of the corrugations of said portion internally thereof and covering the spaces between them over an area confined substantially to the base so as to present a surface along said base, that is substantially free of depressions and a film of paint-like nature extending upwardly along the inside of the culvert as a continuation of the filling.
13. A circumferentially corrugated culvert having the interior thereof at least coated with an adhesive, resilient substance covering at least a substantial portion of the lower half of the culvert, but so applied along the base of the culvert as to be substantially thicker than as applied to the side walls.
14. A sheet metal culvert or the like having a cylindrical body corrugated circumferentially, and hence transversely to its length, and a coating within the said body of a closely adherent, resilient bituminous material of asphaltic nature, said coating being applied as a paint-like protective film to a lower portion of the body at least, but substantially filling the corrugations along the base of the body lengthwise thereof as if to a liquid level reaching to the crests of the corrugations and covering them, thereby providing a substantially level floor along the base of the culvert exclusively, as and for the purpose described.
15. A sheet metal culvert or the like having a galvanized cylindrical body corrugated circumferentially, and hence transversely to its length, and a coating within the said body of a closely adherent, resilient bituminous material of asphaltic nature, said coating being applied as a paint-like protective film to a lower portion of the body at least, but substantially filling the corrugations along the base of the body lengthwise thereof, as if to a liquid level reaching to the crests of the corrugations and covering them thereby providing a substantially level floor along the base of the culvert exclusively, as and for the purpose described.

ALLERTON S. CUSHMAN.
